ROTARY PUMP

John Henry Rowlands, Saundersfoot, and Griffith
Thomas, Begelly, WalesApplication December 1, 1931, Serial No. 578,238,
and in Great Britain December 31, 1930

3 Claims. (Cl. 103—128)

This invention relates to rotary pumps of the kind wherein two rotors in rolling contact and provided with intermeshing projections and recesses, are enclosed in two intersecting cylinders 5 furnished with inlet and outlet ports adjacent to their lines of intersection, and has for its object to provide an improved construction whereby increased efficiency and convenience in operation may be attained.

10 According to the present invention the intermeshing projections and recesses are arranged helically upon the rotor, the leading part of each projection being furnished on its trailing side with a straight portion extending longitudinally 15 of the rotor. Preferably the inlet port is reduced in width at that side adjacent to the trailing ends of the projections. Preferably also, the helical projections are of progressively decreasing thickness from their leading to their trailing ends. 20 The outlet port may be provided with a non-return flap-valve constituted by a plurality of valve flaps formed, with the exception of the outer one, with apertures of progressively decreasing areas and being hinged each to the preceding flap excepting the inner one which is 25 hinged to the pump framework. The stuffing box glands for the rotor shafts may be formed with teeth at their peripheries so as to engage with a pinion mounted upon a shaft carrying a 30 handwheel or the like, so as to be adapted to be rotated simultaneously for tightening the glands.

The invention will be described by way of example with reference to the accompanying drawings of which Figure 1 is an end elevation of a 35 pump with the end plate of the casing removed, Figure 2 is a sectional elevation taken on the line 2—2 of Figure 1, Figure 3 is an elevation of a rotor showing a modification and Figure 4 is a perspective view of a rotor as illustrated in Figures 40 1 and 2 showing the position of the inlet port relatively to the rotor.

As shown in Figures 1 and 2, a rotary pump consists of a casing 11 divided into two similar compartments by means of a plate 12 and closed 45 by means of end plates 13 and 14, the casing 11 being furnished with holding-down bolts such as 11a. In each of said compartments is disposed a pair of coating rotors 15, 16 and 17, 18 of which the rotors 15, 17 and 16, 18 are mounted 50 on common shafts 19 and 20 respectively, said shafts passing through the division plate 12 and being mounted in bearings in the end plates 13 and 14.

The casing 11 is furnished on its opposite sides 55 with an inlet 21 and an outlet 22, together with

corresponding inlet and outlet ports 23 and 24 respectively, the latter being provided with a non-return flap valve constituted by a plurality of valve flaps 25, 26, 27, 28 and 29 of which the flaps 25, 26, 27 and 28 are formed with apertures 60 such as 30 of progressively decreasing areas, and of which the flaps 26, 27, 28 and 29 are hinged each to the preceding flap, the flap 25 being hinged as at 31 to the casing 11.

Each rotor of a pair of coating rotors such as 15, 16 is formed with two projections such as 32 which are of helical formation for the major part of their lengths and straight for the remainder as at 33, the straight portion 33 being at the leading end 33a of the helix, and in particular, on the trailing side 32a of the projection 32. Recesses such as 34 are formed adjacent to the projections on the one rotor for the accommodation of the corresponding projections on the other rotor of the pair. 75

The inlet port 23 is formed with lips 35 adjacent to the trailing ends of the projections 32 so as to reduce its width at that point, whilst if desired similar lips (not shown) may be provided in the outlet port 24. It will be appreciated that the 80 lips 35 (dotted lines on Figure 4) cause the inlet port to close earlier than would otherwise be the case, and thus enable the helical projections 32 to be made of smaller pitch without risk of direct communication between the inlet and outlet 85 ports.

The shafts 19 and 20 are geared together at one end by means of pinions 36 and 37 so as to be constrained to rotate at equal speeds, whilst stuffing box glands 38 and 39 serving to make the 90 bearings of the shafts 19 and 20 watertight, are formed at their peripheries with teeth 40 so as to engage with a pinion 41 mounted on a shaft 42 carrying a handwheel 43 for the purpose of tightening said glands equally. The shaft 42 is 95 mounted at one end on the end plate 13 and extends through the wall of a cover 44 which serves to protect the gearing and is furnished with an inspection cover 44a and a drain plug 44b. The shafts 19 and 20 extend through the end plate 14 in bearings furnished with packing glands 38a and 39a similar to the glands 38 and 39. 100

Adjacent to the outlet port 24 is mounted a pair of rotary brushes or scrapers 45, 45 connected by 105 gearing (not shown) with the rotor shafts 19, 20 so as to be adapted to rotate in contact with the surfaces of the adjacent rotors. Each scraper 45 is furnished with a sharp edged projection 46, and with bent wire teeth 47 similar to those employed on card clothing, the arrangement being 110

such that any foreign matter adhering to the rotors will be removed by the scrapers 45 and carried to the outlet.

Figure 3 shows a modified rotor 48, having a 5 pair of helical projections 49, 50 united by a straight portion 51 at their leading ends, two of such pairs 49, 50 being provided on each rotor.

By means of this invention a rotary pump may be so constructed that greater volumetric efficiency and a more uniform flow of fluid may be attained than heretofore whilst a relatively small pitch helix may be adopted for the helical projections, thus increasing the speed at which the machine may be operated efficiently.

15 We claim:—

1. A rotary pump comprising two intersecting cylinders, two power driven rotors in said cylinders, the entire cylindrical surfaces of which rotors are in rolling contact except for two 20 diametrically opposite helical projections and two cooperating recesses adjacent said projections, the

faces of said projections and the adjacent recesses being continuous, the arrangement being such that the projections of one rotor intermesh with the recesses of the other rotor, straight portions extending from the trailing sides of the leading ends of the respective projections and recesses parallel with the axes of the rotors, and inlet and outlet ports on opposite sides of and at right angles to an axial plane of said cylinders and adjacent the lines of intersection of the latter.

80
85

2. The rotary pump as in claim 1 wherein said helical projections and cooperating recesses decrease in width from their leading ends to their trailing ends.

3. The rotary pump as in claim 1 wherein the 90 inlet port at the intersection of said cylinders is reduced in width adjacent the trailing ends of said projections.

JOHN HENRY ROWLANDS.
GRIFFITH THOMAS.
